(57) **CLAIM**

We claim the ornamental design for a liquid disinfectant dispenser spout, as shown and described.

DESCRIPTION

FIG. 1 is a perspective view of the liquid disinfectant dispenser spout of the present invention within the environment of an exemplary bottle and dispenser shown in broken lines and forming no part of the claimed design;

FIG. 2 is a top plan view thereof;

FIG. 3 is a bottom plan view thereof;

FIG. 4 is a left-side elevational view thereof;

FIG. 5 is a front elevational view thereof;

FIG. 6 is a back elevational view thereof; and,

FIG. 7 is a right-side elevational view thereof.
